by Wallace R. Lane Atty.

UNITED STATES PATENT OFFICE.

RALPH BUIT, OF MUSKEGON, MICHIGAN, ASSIGNOR TO THE ALASKA REFRIGERATOR COMPANY, OF MUSKEGON, MICHIGAN, A CORPORATION OF MICHIGAN.

BRINE-TANK HANGER.

Application filed August 28, 1926. Serial No. 132,147.

This invention pertains to a device to be employed when it is desired to convert a refrigerator originally designed to use ice into a refrigerator using artificial refrigeration apparatus. It is often desired to install such apparatus in a refrigerator having a compartment originally designed to hold ice. There are various units on the market at present designed for this purpose and it has been found that the difficulty of mounting these units in refrigerators has entailed a considerable labor expense. In order to reduce the amount of this labor item and in order to provide a satisfactory means for hanging a brine tank in the refrigerator compartment I have designed a device hereinafter described.

One of the objects of this invention is to provide a brine tank hanger which may be adapted to support brine tanks of various dimensions.

Another object of this invention is to provide a hanger that may be readily installed in a refrigerator compartment without piercing the insulation of the ice box.

Another object of this invention is to provide such a hanger as may be installed with a minimum of labor.

Another object is to provide a hanger of rigid construction which will satisfactorily hold a tank firmly in position even when the refrigerator is moved about the house.

Another object of this invention is to provide a brine tank hanger having all the above advantages and which will permit the quick and easy removal of a brine tank whenever that seems desirable.

Further objects, advantages and capabilities will later appear and are inherently possessed by this invention.

My invention further resides in the combination, construction and arrangement of parts illustrated in the accompanying drawing, and, while I have shown therein a preferred embodiment, I wish it understood that the same is susceptible of modification and change without departing from the spirit of my invention.

In the drawing which has been selected to illustrate the invention,

Fig. 1 is a perspective view with portions cut away of a compartment of a refrigerator showing the brine tank hanger secured therein.

Fig. 2 is a top plan view of the hanger showing it secured to the walls of the compartment.

Fig. 3 is a fragmentary cross section taken on the line 3—3 of Fig. 2 through one of the clamping means on the brine tank hanger.

Referring in greater detail to the drawing a compartment 1 of a refrigerator is shown with a portion cut out with the brine tank hanger located near the top of the compartment. The outside frame members 2 of the hanger may be secured to the wall 3 of the compartment by means of screws 4, or in any other suitable manner. Two of the frame members may be angle irons as illustrated and the other two opposing frame members may be made from flat stock as illustrated, however, I do not confine myself to the use of this stock in these frame members.

Slidable along the frame members and resting upon the top of the angle irons are transverse brace members 5 which may be channel iron, as illustrated, or may be of some other desirable construction. Passing through a hole provided in the member 5 is a bolt 6 retaining a washer 7, or the like, below the brace member and threading into a nut 8 or a similar threaded article which is located on the top side of the brace member. The nut 8 may be held against rotation in any suitable manner. The washer 7 is of such diameter as to cause a supporting member 9 to press against the under side of the angle iron which forms the brace member 2. The supporting member 9 in which the brine tank 10 may be suspended may be of any desired construction and may be provided with such an aperture as will permit the bolt 6 to be passed therethrough. Inasmuch as the four bolts 6 may be readily unscrewed or screwed it can be understood that the brace members 5 may be readily moved horizontally along the frame members 2, in order to retain the supporting members 9 in a proper spaced relation. This adjustability is desirable for the reason that the brine tanks now put on the market by various manufacturers are not all of the same size, but experience has shown that they all may be supported on the brine tank hanger illustrated and in the manner shown and described.

Whenever it is desired to remove the brine

tank it can be seen that a support may be very easily detached from the hanger. It is evident that this device lends itself to the easy installation of artificial refrigeration apparatus in a refrigerator. The screws 4 entering the side walls of the compartment do not pierce the insulation. It has been the practice in the past in many cases to pass bolts through the top of the compartment in order to provide a sufficient support for a brine tank. Such piercing of the insulation of a refrigerator is manifestly undesirable. Hitherto the labor cost of installation of this equipment has been rather high due to the past unsatisfactory means for attaching the brine tanks together with the fact that the skilled labor employed in this art is expensive.

Not only is my adjustable brine tank hanger a great aid to low installation cost but it is apparent that it very firmly and rigidly holds a brine tank in the desired position and gives assurance that the apparatus will not be thrown out of alignment whenever it becomes necessary to move a refrigerator about a house.

It is contemplated that, whenever necessary, additional holes may be provided in the brace members to be used in connection with the support for the tank, or other clamping means than that which is illustrated may be employed.

Having shown and described my invention,

35 I claim:—

1. A brine tank hanger comprising a frame adapted to be secured in a refrigerator, a plurality of slideable bars resting upon the frame and means for clamping said bars in a plurality of positions on the frame.

2. A brine tank hanger comprising a frame adapted to be secured in a refrigerator, a plurality of bars slideable on said frame, and means for clamping said bars in a plurality of positions on the frame, the said means

being further adapted to provide attaching means for a tank support.

3. A brine tank hanger comprising a frame adapted to be secured in a refrigerator compartment, and clamping means horizontally slideable along the frame for providing attaching means for a tank support at a plurality of positions.

4. A brine tank hanger comprising a frame adapted to be secured in a refrigerator compartment, and members horizontally slideable along said frame for providing attaching means for a tank support and for rigidly spacing apart the said attaching means.

5. A brine tank hanger comprising a pair of members adapted to be secured to the inner walls of a refrigerator compartment, brace elements horizontally supported on said members and means for clamping said elements to said members, said means being further adapted to serve as attaching means for supporting members extending upwardly from a brine tank.

6. A brine tank hanger comprising a frame adapted to be secured in a refrigerator, a plurality of bars slideable on said frame, and means for clamping said bars in a plurality of positions on the frame.

7. A brine tank hanger comprising a frame adapted to be secured in a refrigerator, a tank support, and clamping means horizontally slideable along the frame for providing attaching means for the tank support at a plurality of positions.

8. A brine tank hanger comprising a frame adapted to be secured in a refrigerator compartment, a tank supporting member, and members horizontally slideable along said frame for providing attaching means for said tank support member and for rigidly spacing apart the said attaching means.

In witness whereof, I hereunto subscribe my name to this specification.

RALPH BUIT.
